UNITED STATES PATENT OFFICE.

EDGAR C. LITCHFIELD AND HENRY L. LITCHFIELD, OF WEBSTER CITY,
IOWA.

DESIGN FOR A GRAIN-GRINDER.

SPECIFICATION forming part of Design No. 34,793, dated July 16, 1901.

Application filed May 13, 1901. Serial No. 60,125. Term of patent 14 years.

To all whom it may concern:

Be it known that we, EDGAR C. LITCHFIELD and HENRY L. LITCHFIELD, citizens of the United States, residing at Webster City, in the county of Hamilton and State of Iowa, have invented and produced a new and original Design for a Grain-Grinder, of which the following is a specification.

This invention relates to a new and original design for a grain-grinder; and the essential features consist of a regularly-positioned frusto-conical section rising from a sloping base with a projection of the form shown.

The accompanying drawing shows a perspective view of the grinder embodying the features of the design.

The numeral 1 designates a frusto-conical section which is regularly positioned and rises from an inwardly-sloping base 2, provided with an angular projection 3 at the front, the upper end of said base being in the form of

a horizontal flat rim 4. The base 2 is supported by a polygonal rest 5, and the front projection 3 has thereunder a front projected portion of the said rest, said projection having a flat surface member 6, which is inwardly inclined. On the section 1 an inverted conical section 1^a is mounted, and on said latter section is a hopper-like device 7.

Having thus described the invention, what is claimed as new is—

The design for a grain-grinder, as herein shown and described.

In testimony that we claim the foregoing as our own we have hereto affixed our signatures in the presence of two witnesses.

EDGAR C. LITCHFIELD.
HENRY L. LITCHFIELD.
